[57] CLAIM

The ornamental design for a circumcision clamp, as shown and described.

DESCRIPTION

FIG. 1 is a top perspective view of a circumcision clamp showing our new design;

FIG. 2 is a bottom plan view thereof;

FIG. 3 is a front side view thereof;

FIG. 4 is a rear side view thereof;

FIG. 5 is an end view thereof, taken from the left end of FIG. 1;

FIG. 6 is an end view thereof, taken from the right end of FIG. 1;

FIG. 7 is a top plan view thereof, with the tool open and the lever swung outward;

FIG. 8 is a top plan view thereof, with the lever engaged and unlocked; and

FIG. 9 is a top plan view thereof, with the lever locked.

FIG. 1

FIG. 2

FIG. 3

FIG. 4

FIG. 5

FIG. 6

FIG. 7

FIG. 8

FIG. 9
